UNITED STATES PATENT OFFICE.

ISAK MYHRE HOFSTAD, OF WRANGELL, DISTRICT OF ALASKA.

PARALLEL-RULER.

No. 823,865.

Specification of Letters Patent.

Patented June 19, 1906.

Application filed December 26, 1905. Serial No. 293,256.

To all whom it may concern:

Be it known that I, ISAK MYHRE HOFSTAD, a citizen of the United States, and a resident of Wrangell, in the District of Alaska, have 5 invented a new and Improved Parallel-Ruler, of which the following is a full, clear, and exact description.

The invention relates to drafting; and its object is to provide a new and improved parallel-ruler more especially designed for the use of mariners, draftsmen, and other persons and arranged to prevent slipping on the chart or drawing and to allow accurate ruling from one place to another—for instance, 15 when laying out a course on a map and moving the instrument over to the compass.

The invention consists of novel features and parts and combinations of the same, which will be more fully described herein- 20 after and then pointed out in the claims.

A practical embodiment of the invention is represented in the accompanying drawings, forming a part of this specification, in which similar characters of reference indicate corresponding parts in all the views.

Figure 1 is a plan view of the improvement. Fig. 2 is an enlarged sectional side elevation of one end of one of the cylinders. Fig. 3 is a like view of the other end of the cylinder, and 30 Fig. 4 is an enlarged transverse section of the improvement.

The parallel members of the ruler are in the form of rollers or cylinders A and A', preferably made of glass or other transparent material, and each of the said cylinders A and A' is provided at its ends with bands B, of rubber or other material, adapted to roll on the map, chart, or drawing without danger of slipping. In the cylinders A and A' 35 are arranged pistons C and C', of which the piston-rod C² of the piston C extends centrally through a bearing D, secured in one end of the cylinder A, the outer end of the piston-rod C² terminating in an L-shaped extension C³, having a head C⁴ engaging a bearing D', secured in one end of the other cylinder A'. (See Figs. 1 and 2.) In a like manner the piston C' in the cylinder A' has its piston-rod C⁴ extending through a bearing 40 D², secured in the end of the cylinder A' opposite the one carrying the bearing D', and the outer end of the said piston-rod C⁴ terminates in an L-shaped extension C⁵, having a head similar to the head C⁴ and engaging a bearing D³, fixed in the end of the cylinder A 45 opposite the one carrying the bearing D.

The L-shaped extensions C³ and C⁵ of the piston-rod C² and C⁴ are preferably provided with suitable handles E, adapted to be taken hold of by the operator for conveniently rolling the parallel-ruler over the map, chart, drawing, or the like.

By the arrangement described the cylinders A and A' can be conveniently adjusted in the direction of their length, at the same 60 time maintaining their parallelism, and the cylinders can be conveniently and accurately rolled over the drawing, chart, or map without danger of slipping, owing to the arrangement of the rubber bands B at the ends of the 65 cylinders.

The cylinders A and A' are preferably provided with longitudinally-extending guiding-lines F, etched or otherwise formed on the outer surface of the cylinder A and preferably colored—say red—so as to be readily discernible. On the lines F may be arranged 70 graduations, indicating miles, kilometer, or other linear measurements.

The parallel-ruler shown and described is 75 very simple and durable in construction, can be cheaply manufactured, and by having the cylinders A and A' made of glass the user is readily enabled to view lines on the chart or map directly under the cylinders.

Having thus described my invention, I 80 claim as new and desire to secure by Letters Patent—

1. A parallel ruler, comprising a pair of transparent cylinders, and means for retaining 85 said cylinders in parallelism and permitting movement of the cylinders longitudinally with respect to each other.

2. A parallel-ruler, comprising a pair of parallel cylinders, and pistons mounted to 90 slide therein, the piston-rod of the piston in one cylinder being connected with the other cylinder.

3. A parallel-ruler, comprising a pair of glass cylinders having bearings in their 95 ends, pistons movable in the said cylinders, and piston-rods for the said pistons, the piston-rod in one cylinder extending through one of the bearings thereof, to engage a bearing in the other cylinder.

In testimony whereof I have signed my name to this specification in the presence of two subscribing witnesses.

ISAK MYHRE HOFSTAD.
